UNITED STATES PATENT OFFICE.

AARON M. WEBER, OF OSHKOSH, WISCONSIN.

COMBINED DRESS-FACING AND SKIRT-BINDING.

SPECIFICATION forming part of Letters Patent No. 562,943, dated June 30, 1896.

Application filed May 18, 1896. Serial No. 591,918. (No model.)

To all whom it may concern:

Be it known that I, AARON M. WEBER, a citizen of the United States, residing at Oshkosh, in the county of Winnebago and State 5 of Wisconsin, have invented new and useful Improvements in a Combined Dress-Facing and Skirt-Binding, of which the following is a specification.

My invention relates to a combined water- 10 proof binding and skirt-facing for bicycle-skirts.

Heretofore great discomfort has been experienced by ladies in riding bicycles, owing to the fact that with ordinary bindings the 15 skirt is too light, and when weighted with lead or equivalent materials it hangs unevenly and flaps against the limbs, to the great annoyance of the wearer. The weighted parts also wear out at the bottom and render 20 the skirt unsightly.

The object of my invention is, first, to provide a combined skirt binding and facing especially adapted to be used by bicycle-riders, which will not only serve as a binding 25 and facing, but which will add uniformly to the weight of the lower edge of the skirt, and at the same time stiffen it sufficiently to prevent it from hanging against the limbs of the wearer, and, second, to provide for the con- 30 struction of the binding as an article of manufacture adapted to be very easily and quickly attached to the dress without the necessity of sewing by hand through the stiffened portion.

35 In the following description reference is had to the accompanying drawings, in which—

Figure 1 is a side view of my invention. Fig. 2 is an enlarged edge view of my invention. Fig. 3 is also an edge view showing the 40 binding in process of attachment to the skirt, with dotted lines indicating its attached position.

Like parts are identified by the same reference-letters throughout the several views.

45 A strip of velvet or other suitable cloth A is cut bias and lined with any suitable material, the lining B being secured to the vel-

vet by means of a solution of rubber, which renders it waterproof. The strip is then folded and a strip of tape C is preferably 50 sewed between the respective sides to prevent stretching. This tape, however, may be omitted if desired. I then take ordinary dress-goods D, cut the same bias, and attach a lining E to it by means of rubber cement in the 55 same manner that the strip A is prepared, as above described, thus forming a wide facing of rubber cloth for the lower part of the skirt. The facing is then laid upon the folded strip A with the edges together, and the facing and strip A are secured together by stitching. The upper edge of the facing is provided with a strip of tape F, which facilitates its attachment to the dress, it being preferable to do 60 the stitching to the dress by hand, and the 65 rubber cement rendering it difficult to pass a needle through the facing.

In attaching my facing to the skirt, the prepared strip is first laid in reversed position on the outside thereof, as shown in Fig. 3, 70 and sewed thereto near the lower edges, the strip being then folded over on the inner side of the skirt, and secured to the dress-lining by stitching through the braid F, the latter being the only case where a machine cannot 75 well be used.

It will be observed that I have thus provided a dress binding and facing formed into a single article of manufacture of sufficient weight and stiffness to make it hang prop- 80 erly, and waterproof throughout. It is very quickly and easily attached to the skirt and can be washed off when soiled without removing it.

Having thus described my invention, what 85 I claim as new, and desire to secure by Letters Patent, is—

1. A combined dress facing and binding comprising a facing-strip of bias-cut water- 90 proofed cloth having along its outer face at the lower edge a longitudinally-folded bias-cut waterproofed binding, said binding being secured to the facing with its free edges flush with lower edge thereof, as set forth.

2. A combined dress facing and binding comprising a facing-strip of bias-cut water-proofed cloth having along its outer face at the lower edge a longitudinally-folded bias-cut water-proofed binding, said binding being secured to the facing with its free edges flush with the lower edge thereof, said facing having along its inner face at the upper edge a

narrow tape, said tape projecting above the edge of the facing, as set forth. 10

In testimony whereof I affix my signature in the presence of two witnesses.

AARON M. WEBER.
